UNITED STATES PATENT OFFICE.

OLOF SWANSON, OF ATCHEE, COLORADO.

LUBRICATING DEVICE.

1,163,434.

Specification of Letters Patent. Patented Dec. 7, 1915.

Application filed January 16, 1915. Serial No. 2,599.

To all whom it may concern:

Be it known that I, OLOF SWANSON, a citizen of the United States, and a resident of Atchee, in the county of Garfield and State of Colorado, have invented a new and Improved Lubricating Device, of which the following is a full, clear, and exact description.

The invention relates to lubricating devices designed especially for lubricating the flanges of the wheels of railway rolling stock.

My device is characterized by a rolling member which supplies the flange of a wheel with lubricant while in frictional rolling contact therewith.

The object of the invention is to provide a simple, convenient and efficient lubricating device which is mounted adjustably to the flange of a wheel.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a side elevation of a fragment of railway rolling stock the wheel of which is provided with an embodiment of my invention; Fig. 2 is a front elevation of my lubricating device; Fig. 3 is a side elevation as seen in the direction of the arrow 3 in Fig. 2; Fig. 4 is a plan view; Fig. 5 is a horizontal section on line 5—5, Fig. 2, showing the lubricating part of the device only; Fig. 6 is a section on line 6—6, Fig. 5; and Fig. 7 shows a plan view of a modified structure of my device; and Fig. 8 is a cross-sectional view on line 8—8, Fig. 7.

Referring to the drawings, 7 represents a wheel of a vehicle of railway rolling stock. Attached to the vehicle adjacent the wheel is a clamp 8 in which a bracket 9 is adjustably mounted. The bracket 9 is in the shape of a square, one branch of which is rectangular and engaged by the clamp 8, while the other branch is round and is directed parallelly to the axis of the wheel. Mounted to turn and slide on the round arm of the bracket is a support 10 which is provided with a pair of set screws 11 whereby said support can be clamped to the bracket in any posi-

tion. A lubricant receptacle 12 is connected to the support 10 by a bolt 13, which constitutes the pivot for said lubricant receptacle 12 and which permits to the same a swinging movement on the support to and from the flange of the wheel 7. The support 10 is also provided with a resilient member 14 one end of which abuts against a stud on the support and the other end against the lubricant receptacle 12, whereby the same is constantly forced by the spring to move toward the flange of the wheel.

The lubricant receptacle adjacent its pivot is provided with an inlet 15 which may be connected to a suitable lubricant supply or it may be closed by a plug when the lubricant is fed into the receptacle intermittently. The end of the receptacle which is adapted to engage the wheel is provided with a threaded plug 16 the threaded end of which forms a seat for the ball 17 retained in place by a sleeve 18 threaded to the plug 16. The plug 16 has a reduced opening 19 which leads to the seat and through which the lubricant finds its way to the ball. The end of the receptacle provided with the ball is bent to face the flange portion of the wheel so that the ball 17 will contact with said flange portion without any danger of interference between the wheel and the receptacle 12.

The lubricant stored in the receptacle 12, or supplied thereto continuously, will contact with the ball 17 through the opening 19 in the plug 16. The rotation of the ball 17, due to its frictional contact with the flange of the wheel, will transfer the lubricant from the receptacle to the flange whenever there is a rotation of the ball by the wheel. The resilient member 14 maintains the contact between the ball 17 and the flange of the wheel, no matter how irregular the flange surface of the wheel 7 may be. The clamp 8 permits the vertical adjustment of the lubricating device; while the set screws 11 permit any adjustment of the lubricating device to and from the flange, so that the pressure of the spring 14 may be varied thereby. By means of said set screws the lubricating device can be inclined on the bracket so as to cause a gravitational feeding of the lubricant toward the ball if desired.

The support 10 is also provided with an opening 20 into which a pin can be inserted

and thereby the lubricant receptacle 12 locked in its movement and the ball 17 prevented from contacting with the flange of the wheel 7. The opening in the clamp 8 for the bracket 9 is preferably large enough to allow a turning movement to the bracket to bring the ball 17 in contact with any desired part of the flange of the wheel. By means of the opening 20 in the support the lubricating receptacle can be brought in contact with the flange or disengaged therefrom.

In Figs. 7 and 8 the lubricating receptacle 12' is mounted on a bolt 13' which forms the pivot therefor and which bolt is set obliquely on the support 10'; consequently, the force of gravity will cause the lubricant receptacle to move toward the side to which the bolt 13 is inclined; and by directing the inclination of the bolt 13' toward the side of the flange of the wheel, gravity will normally drive the lubricant receptacle 12' against the flange of the wheel without the aid of any resilient member. The movement of the lubricant receptacle on the platform is limited by pins 21 and 22.

From the foregoing description, taken in connection with the accompanying drawings, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such changes may be made as are within the scope of the appended claims.

Having thus described my invention, I claim as new and desire to secure by Letters Patent:

1. In a lubricating device, a lubricant receptacle mounted to swing, a ball free to roll adapted to contact with the lubricant in the receptacle and with the surface to be lubricated, and resilient means for swinging the receptacle for maintaining the engagement between said rolling member and the surface to be lubricated.

2. In a lubricating device, a receptacle for a lubricating medium mounted to swing at one end thereof, a ball, free to rotate in the other end of the receptacle, adapted to contact with the lubricant in said receptacle and roll on the surface to be lubricated, and a resilient member for swinging the receptacle to maintain the contact between said ball and the surface to be lubricated.

3. In a lubricating device, a receptacle for lubricant mounted to swing at one end thereof, a ball retained in the other end of said receptacle and partly exposed therefrom, said receptacle having means for supplying lubricant to said ball, said ball being free to rotate in the end of said lubricant receptacle.

and adapted to contact with the surface to be lubricated, and a resilient member tending to swing said receptacle whereby said ball is maintained in contact with the surface to be lubricated.

4. In combination with the flange of a railway vehicle wheel, an adjustably mounted support, a receptacle for lubricant, a bolt connecting one end of the receptacle to the support and forming a pivot for said receptacle, a ball mounted to roll in and projecting from the other end of the receptacle, said receptacle having means establishing communication between the ball and the lubricant in the receptacle, and a resilient member on the support engaging said receptacle whereby the ball is forced into contact with the flange of the wheel.

5. In combination with the flange of a railway vehicle wheel, a clamp, a support engaged by the clamp, a receptacle for lubricant, a bolt connecting one end of the receptacle to the support and constituting a pivot for said receptacle whereby the same is free to swing to and from the flange of the wheel, a plug at the other end of the support forming a seat for a ball, a ball mounted to roll on said seat, a retainer for said ball connected to the plug and through which retainer the ball projects, said plug having an aperture establishing communication between the seat and the receptacle, and a resilient member on said support normally forcing the receptacle to move toward the flange, whereby the contact between the ball and the flange is maintained.

6. In combination with the flange of a railway vehicle wheel, a clamp, a square-shaped bracket having one arm rectangular in cross section and the other round, said rectangular arm being engaged by the clamp, a support mounted to slide and swing on said round arm of the bracket, means for clamping said support to the arm, a receptacle for lubricant, a bolt connecting one end of the receptacle to the support whereby the same is free to swing to and from the flange, the other end of said receptacle being curved toward the flange of the wheel, a plug engaging the curved end, said plug having a seat for a ball, a ball mounted to roll in the seat, a retainer for the ball engaging the plug and through which the ball projects, said plug having a passage establishing communication between the seat and the receptacle, and a resilient member on the support engaging the receptacle whereby said ball is maintained in engagement with the flange of the wheel.

7. In a lubricating device, a lubricant receptacle mounted to swing at one end thereof, the axis on which said receptacle is mounted to swing being oblique to the longitudinal axis of said receptacle, a rolling member at the other end of said receptacle

adapted to contact with the lubricant in the receptacle and with the surface to be lubricated, and means limiting the movement of said receptacle on its axis.

5 8. In a lubricating device, a receptacle for a lubricating medium disposed in a substantially horizontal plane, a bolt engaging one end of said receptacle and on which bolt said receptacle is mounted to swing, said bolt being inclined to the longitudinal axis of said receptacle whereby gravity causes said receptacle to swing toward the side to which the bolt is inclined, a ball free

to rotate in the other end of the receptacle, said ball being adapted to contact with the 15 lubricant in said receptacle and roll on the surface to be lubricated, and means limiting the swinging movement of said receptacles.

In testimony whereof I have signed my name to this specification in the presence 20 of two subscribing witnesses.

OLOF SWANSON.
